METHOD OF TREATING OIL WELLS

Eugene A. Stephenson, Lawrence, Kans., assignor
to The University of Kansas Research Foundation,
Lawrence, Kans., a corporation of Kansas

Application November 8, 1943, Serial No. 509,372

2 Claims. (Cl. 166—21)

This invention relates to the art of treating oil wells of that type wherein an objectionable amount of water has appeared, or which is producing an undesirable amount of water with the oil.

The primary aim of this invention is to provide a method of treating an oil well of the aforementioned type to reduce its production of water.

An even further object of this invention is to provide a method of treating oil wells in water bearing formations, which includes the steps of forcing oil into the water bearing portion of said formation at a velocity and pressure sufficient to increase the oil saturation within the said formation and to inhibit the entrance of water into the well.

A further object of the invention is the provision of a method of treating oil wells which includes the steps of forcing oil into the water bearing portion of the producing formation at a velocity and pressure sufficient to increase the oil saturation within the formation around the well bore to inhibit the entrance of water into the well because of the formation of an emulsion.

This application is a continuation in part of my co-pending application Serial No. 492,700, filed June 29, 1943, for Method and apparatus for treating oil wells.

A still further object of the invention is the provision of a method of treating oil wells wherein a column of oil and water has appeared, which includes segregating a portion of the well bore to set off a part of the face of the producing formation, and thereafter introducing oil under high pressure into the segregated portion and thence into the said formation to displace the water therein.

This invention has for a further object to provide novel, simple, and efficient apparatus for carrying out the several steps of the aforementioned method.

Another object of the invention is to provide apparatus for segregating a portion of the well bore, whereby one of the steps of the invention may be practiced, i. e., that of injecting oil under high pressure into a selected part of the formation.

A further object of the invention is to provide an apparatus for treating oil-water wells that permits segregating a portion of the well bore for the injection of oil under high pressure into a selected part of the formation without first removing the water from the well.

When practicing the invention as set forth in the foregoing objects, and through employment

of apparatus about to be described, the same will be capable of a large number of specific applications. For example, in the treatment of wells used in artificial water flooding operations where it becomes desirable to reduce the permeability of streaks of the formation into which excessive portions of injected water penetrate and thus reduce the effectiveness of the flooding process in other less permeable streaks.

10 The method is also applicable to the treatment of high gas-oil ratio wells through the injection of oil under pressure into selected portions of the producing formation.

The drawing illustrates an oil well partially 15 in section, having apparatus associated therewith that permits practicing the method embodying this invention.

In the drawing, numeral 2 designates the conventional casing which has its end 4 spaced from 20 the bottom of the bore 6. In some practices 2 extends to the bottom of the well and is perforated adjacent to the producing section of the formation. Cement 56 fills the space between casing 2 and the natural rock 58. Upon the free 25 end of casing 2 is a conventional high pressure casing head 8 with suitable packing therein through which tubing 14 extends to a cross 10. One opening of the cross 10 is connected by means of pipe 12, with valve 16 therein, to gauge 30 18 for the measurement of the pressure in tubing 14. One side of the cross 10 is connected by means of pipe 20, with valves 22 therein, to a tank or other source of supply, not here shown. The other opening of cross 10 is closed by means 35 of a conventional bull plug 54.

Tubing 14 is of any conventional type within which the usual sucker rods are confined when the well is under normal operation.

40 The high pressure casing head 8 is also fitted with a pipe 42, having a pressure gauge 46 in connection therewith for the measurement of pressures within the space 48 between casing 2 and pipe 14, or for the connection of other devices 45 which are commonly used for the measurement of fluid levels in oil wells. A valve 44 should be interposed in pipe 42.

Similarly pipe 50 having valve 52 placed therein, is attached to the other opening in casing head 8 through which fluid may be introduced from tank or pump (not shown), into the space 55 48 between tubing 14 and casing 2.

The oil producing formation is of a character that might be encountered at any location where the oil is under what is known as natural or

artificial water drive, or drive due to solution gas or gas cap gas.

In the drawing the oil producing zone is shown diagrammatically at 24 with zones 26 and 28 below it designated as the oil-water zone. The line of demarcation between 24 and 26 varies in the degree of abruptness at 30, but is usually characterized by low water saturation in the lower part of 24 and the upper part of 26 with progressive increase in water saturation with depth below the oil-water contact 30. The contact zone is normally the zone in which capillary rise exists above a fixed plane of complete water saturation. Similarly, the gas-oil contact (not shown), represents a zone of progressively greater oil saturation when passing from gas to oil zones. The rate of increase in water saturation with depth in zone 24-26, is also a function of the permeabilities of the various streaks within the formation. Zone 24-26 may also contain slugs or pockets of oil which may become recoverable through the reduction in permeability to water in zone 24-26.

Area 28 is a diagrammatical representation of what is commonly designated as a "water-cone" in and around oil-water producing wells. Within such area 28 the natural oil-water saturations have been greatly modified by water encroachment and the formation thus represented has become more permeable to water than to oil.

Among the objects of the invention is to effectively exclude the water in zone 28 from contact with the well bore, prevent the redevelopment of such a zone as 28, and overcome the possibility of water entering the bore 6 due to its rising through tortuous paths or cracks or permeable streaks in the formation 24, 26 or 28. Such cracks or streaks are not illustrated but are well known to those skilled in the art.

The liquid column 32 in well bore 6 usually comprises both oil and water when the necessity for treating the well, in accordance with this method, arises.

In practice of the invention, one of the first steps is to prepare the well for treatment by shutting it down, or in other terminology, "allow the well to stand idle," for a short time so as to reach an approximately stable condition. The exact time will depend upon many factors, but the principal ones will be the productivity of the well itself, the permeability of the formation, the formation pressure, the depth of the well, the production history, and the physical properties of the oil. In actual practice it has been found that many wells reach an equilibrium condition within a period of a few hours, while others require a few days, and others many days. However, those which require extended periods in order to become stabilized, are for all practical purposes, stable during the short period of time which would be required for their treatment according to the method of this invention.

It has been discovered in practice of this invention, that if the oil-water wells are permitted to remain idle for a few days—10 to 20—that in many cases all of the water in said wells will leave the well bores and be replaced by oil, or stated otherwise, oil accumulates on top of the water already in the well and gradually displaces the latter from the well bore. This is termed "gravitational displacement."

Section 36 is equipped with a back pressure valve 38 at its lower end. Packing 34 is also carried by section 36, which is lowered into the

hole as additional joints of pipe are added to tubing 14. When the proper length of tubing has been placed in the hole, packing 34 is expanded to set off the lower portion of bore 6 from that part thereof above seal 34, to form chamber 40.

When oil or other selected liquid is pumped into the bottom of bore 6 through tubing 14, section 36 and back pressure valve 38, disposition of packing 34 insures separation of that section of the well bore opposite the predominantly water-producing formation 26-28 from that section of the well bore opposite the predominantly oil bearing portion of the formation 24. Valve 38 permits passage of oil into chamber 40 and thence through the walls of bore 6 into the water bearing portion of the formation, but prevents any reverse movement of liquid into tubing section 36-14 from bore 6.

The effectiveness of the seal between 34 and the surrounding formation may be greatly improved by the addition of oil on top of oil-water column 32 in annular space 48 through pipe 50 and the casing head 8 until said annular space is full.

When pumping oil into that part of bore 6 below packing 34 (chamber 40), the pressure of injection should be as great as is practicable to cause the oil to enter the formation 26 and 28 at the highest possible rate, so as to reduce the permeability to oil of the water bearing portion of the formation and stimulate the formation of an emulsion within the water bearing portion of the formation. With a portion of bore 6 segregated by seal 34, it is possible to inject oil at a rate sufficiently high to form an emulsion of oil and water within the spaces of the formation 24-26, whereby to inhibit entrance of water into bore 6.

Crude oil which has been produced from the formation to be treated should preferably be used since such oil will be more or less in equilibrium with the minerals and water which are native to the formation. However, it should be noted that such crude oil is not necessary and other suitable liquids may be used. These liquids, specially designed to increase stability (potency), of any emulsion, are available on the open market.

Having thus described the invention, what is claimed as new and desired to be secured by Letters Patent is:

1. The method of treating an oil well which penetrates an oil and water bearing formation and that has a liquid column consisting of both oil and water, which includes the step of setting off a portion of the well bore to create a closed chamber partially walled by the oil and water bearing formation, and injecting oil into said closed chamber at a rate sufficiently great to form an emulsion of oil and water within the interstices of the formation.

2. The method of treating an oil well which penetrates an oil and water bearing formation and that has a liquid column consisting of both oil and water, which includes the step of setting off a portion of the well bore to create a closed chamber partially walled by the oil and water bearing formation, and injecting oil into said closed chamber at a velocity in excess of that at which the well has previously been produced and at a rate sufficiently great to form an emulsion of oil and water within the interstices of the formation.

EUGENE A. STEPHENSON.
